VERTICAL OPPOSED CYLINDER INTERNAL COMBUSTION ENGINE

Original Filed Oct. 11, 1926

FIG. 2.

UNITED STATES PATENT OFFICE

JOHN LAWRENCE BOGERT, OF BROOKLYN, NEW YORK

VERTICAL OPPOSED CYLINDER INTERNAL COMBUSTION ENGINE

Original application filed October 11, 1926, Serial No. 140,852. Divided and this application filed June 13, 1929. Serial No. 371,027.

This application covers matter which originally formed part of patent application Serial No. 140,852, filed October 11, 1926.

My invention relates to improvements in vertical internal combustion engines where power-producing pistons reciprocate in vertical or substantially vertical directions, in contradistinction to horizontal internal combustion engines where power-producing pistons reciprocate in horizontal or substantially horizontal directions; and the objects of my improvements are, first, an engine in which it is possible to have each individual connecting-rod transmit to its crank as much power while moving upward as while moving downward, thereby eliminating a serious difference in the torque developed by the same; second, increased power for a given length of engine; third, reduced bearing friction; and fourth, increased facility for the withdrawal of the pistons. I attain the first of these objects by providing mechanism wherein and whereby all upward-acting power strokes shall exceed in force all downward-acting power strokes by an amount equal approximately to twice the power needed to raise the weight of the reciprocating parts through the vertical height of their reciprocating paths. Thus if p' is the mean piston load during up-strokes and down strokes and s' the length of stroke of the upward power strokes while s'' is the length of stroke of the downward power strokes, $p' \times s'$ must exceed $p' \times s''$ by an amount equal to $2w$ where w is the load on a crank-pin due to the weight of all the parts that reciprocate up and down conjointly with the connecting-rod. Since if $p' \times s' - w$ equals $p' \times s''$ plus w , s' must exceed s'' by $2w$.

It is obvious that since the force developed by the piston in any cylinder depends upon the product of the pressure by the area of the piston multiplied by the stroke, if the pressure and area remain the same the up-strokes must exceed the down strokes in length to develop greater force and power.

I attain the second and third of my objects by employing a swinging beam construction which serves to transmit the upward thrust of a power-producing piston together with the downward thrust of another power-pro-

ducing piston to the same crank-pin through a connecting-rod.

I attain the fourth of my objects by employing open end cylinders and trunk pistons, in place of closed cylinders and double-acting pistons. So that, while my improved engines are true double-acting engines in which all power strokes, whether up or down, may be of equal turning effect, no power-producing piston uses both its upper and its lower face in the development of power. In a previous patent application Serial No. 65,156 filed October 27th, 1925, for improved internal combustion marine engines I have set forth and fully elucidated the prejudicial effect of the weight of the reciprocating parts in all vertical single-acting engines of the steam-hammer type,—which prejudicial effect increases with the increase in the diameter of the pistons.

In the case of double-acting vertical internal-combustion engines of the steam-hammer type this prejudicial effect is so pronounced as to materially alter the stresses transmitted to the cranks on up and down strokes respectively. A double-acting 2-cycle vertical internal combustion engine of the steam-hammer type whose output is as much as 700 to 800 horse-power per cylinder may transmit five times as much power to the crank-shaft during down strokes as during up strokes. It is evident that such engines are uneconomical from a structural point of view, since each crank of the crank-shaft must be strong enough to transmit the maximum stress to which it may be subjected, and economy of material will be secured by reducing all sources of fluctuating torque.

In a double-acting 4-cycle vertical internal combustion engine of the steam-hammer type conditions are much worse, since each crank is subjected to positive torque during 3 consecutive strokes and immediately thereafter to negative torque during the fourth stroke. With 33 inch cylinders this torque fluctuation may be as great as from 1,100 horsepower positive to 700 horsepower negative.

I claim broadly to be the first to discover and point out the important difference be-

tween the power transmitted to the cranks of a double-acting, vertical, steam-hammer type of internal combustion engine during the up and the down strokes, and to have 5 pointed out in this patent application how to design and construct an engine in which, though vertical, no such inequality need exist.

I attain this desired end by means of the 10 mechanism shown in the accompanying drawings. Similar numerals refer to similar parts in the drawings.

Fig. 1 shows a vertical transverse sectional elevation of two opposed cylinders of 15 a group of four whose power-producing pistons, operating on the 4-cycle, transmit through the medium of a swinging beam to a common connecting-rod their alternating thrust; Fig. 2 is a plan view that shows the 20 swinging beam which is a fundamental part of my improved engine construction, and also the way in which the four grouped 4-cycle pistons through their respective links engage pins attached to said swinging beam, 25 so that each 4-cycle piston shall in proper rotation transmit its thrust to said swinging beam and through the beam to a common connecting-rod.

1 is an upper cylinder, 2 an upper cylinder-head and 3 an upper piston. 4 is an upper piston link swivelling on a suitable wrist-pin attached to upper piston 3, and swivellingly attached to a suitable pin 16 to which also is swivellingly attached the 30 upper end of the connecting-rod 17. In Fig. 2 pin 16 is shown engaging the piston links of two upper cylinders at its ends and the connecting-rod 17 at its mid length, swinging beam 13 supporting it on both 35 sides of connecting-rod 17. 5 is a lower cylinder, 6 a lower cylinder-head and 7 a lower piston. 8 is a lower piston link swivelling on a suitable wrist-pin attached to lower piston 7 and swivellingly attached to pin 40 15 on the outer end of swinging beam 13. In Fig. 2 pin 15 is shown engaging the piston links of two lower cylinders at its ends while swinging beam 13 supports it between the same. As fully shown in Fig. 2 swinging beam 13 carries a fulcrum shaft 14 which turns in suitable bearings attached to 45 back framing 23 shown in Fig. 1.

It is easy to see that lower piston 7, though 50 of the same diameter as upper piston 3 and therefore of the same area, develops more power than upper piston 3, owing to its greater stroke, the mean expanding gas pressure in both cylinders 1 and 5 remaining the same. Obviously the stroke of piston 7 55 is to the stroke of piston 3 as the distance of pin 15 from fulcrum 14 is to the distance of pin 16 from fulcrum 14. Hence it is possible to make the displacement swept out by piston 7, which is a measure of its power 60 sufficiently greater than the displacement of

piston 3 to provide for the downward acting weight of the pistons, links, pins, beam and connecting-rod.

Furthermore, the drawings disclose a way in which a 4-cycle engine can be completely 70 double-acting, since one of the two upper pistons 3 has a power stroke when the other has a suction stroke, their motion being downward; and correspondingly one of the two lower pistons 7 has a power stroke when 75 the other has a suction stroke, their motion being upward. Thus the connecting-rod 17 which transmits the motion of beam 13 to crank-pin 18 of crank-shaft 20 is always delivering the thrust of one of the four 4-cycle 80 cylinders 1, 1 and 5, 5 shown in Fig. 2 regardless of whether its motion is up or down. Hence these drawings disclose a true double-acting 4-cycle internal combustion engine.

22 is a bed-plate to which are bolted back 85 frames 23 and front frames 27, the latter shown incorporated with lower cylinders 5. Stays 24 and 25 join front frames 27 and back frames 23. Upper cylinders 1 are bolted to the top of back frames 23 and front 90 columns 12 which are mounted on top of front frames 27. 28 is the upper exhaust manifold and 29 the lower exhaust manifold. The valve gearing is sufficiently shown to indicate both the upper and the lower cylinders 95 operate on the well-known 4-cycle. The introduction into the drawings of more detail is considered objectionable, as tending to obscurity.

Claims.

1. A vertical opposed cylinder internal combustion engine in which power producing pistons reciprocate together in pairs in substantially vertical directions, the lower ones developing power only during up strokes and the upper ones only during down strokes, the lower pistons having the same area but greater stroke than the upper ones, in combination with mechanism for turning reciprocating motion into rotary motion substantially as represented and for the purpose set forth. 105

2. A vertical opposed cylinder internal combustion engine in which the power producing pistons of two single-acting cylinders reciprocate together in substantially vertical directions, whose piston links are swivellingly connected to different pins on the same swinging beam, the piston whose power impulse is exerted during up strokes being connected by its piston link to a pin farther from the fulcrum of said swinging beam than the pin to which is connected the piston link of the piston whose power impulse is exerted during down strokes, the areas of both pistons being the same, in combination with mechanism for turning reciprocating motion into rotary motion substantially as represented and for the purpose set forth. 115

3. A vertical opposed cylinder internal 120

- combustion engine in which the power producing pistons of single-acting cylinders reciprocate together in pairs in substantially vertical directions, whose piston links are 5 swivellingly connected to different pins on the same swinging beam, the piston whose power impulse is exerted during up strokes being connected by its piston link to a pin farther from the fulcrum of said swinging beam than the pin to which is connected the 10 piston link of the piston whose power impulse is exerted during down strokes, the volume swept out by the upward thrusting piston being greater than the volume swept out by the downward thrusting piston, in combination with mechanism for turning reciprocating motion into rotary motion substantially as represented and for the purpose set forth.
- 15 4. A vertical opposed cylinder internal combustion engine in which the power producing pistons of four single-acting cylinders reciprocate together in substantially vertical directions, the power impulses of 20 two being developed only during up-strokes and the power impulses of the other two only during down strokes, the piston links of the two pistons whose power strokes are upward being swivellingly connected to pins on a swinging beam farther from its fulcrum than the pins to which are swivellingly connected the piston links of the two pistons whose power impulses are downward, all the pistons having the same area, in combination 25 with mechanism for turning reciprocating motion into rotary motion substantially as represented and for the purpose set forth.
- 30 5. A vertical opposed cylinder internal combustion engine in which the power producing pistons of four 4-cycle single-acting cylinders reciprocate together in substantially vertical directions, the power impulses of two being developed only during up strokes and the power impulses of the other two only during down strokes, the piston links of the two pistons whose power impulses are upward being swivellingly connected to pins on a swinging beam farther from its fulcrum than the pins to which are 35 swivellingly connected the piston links of the two pistons whose power impulses are downward, the volume swept out by the upward thrusting pistons being greater than the volume swept out by the downward thrusting pistons, in combination with mechanism for turning reciprocating motion into rotary motion substantially as represented and for the purpose set forth.
- 40 6. A vertical opposed cylinder internal combustion engine comprising an upper single-acting cylinder closed at its upper end by a suitable cylinder-head equipped with the necessary valves and valve gearing, and containing a reciprocating piston whose piston link is swivellingly attached to a pin car-
- ried by a swinging beam which oscillates up and down round a fulcrum and transmits rotary motion to a crank-shaft mounted in suitable bearings in a bed-plate thru a connecting-rod, in combination with a lower 70 single-acting cylinder closed at its lower end by a suitable cylinder-head equipped with the necessary valves and valve gearing, and containing a reciprocating piston whose piston link is swivellingly attached to a pin 75 carried by said beam and further from its fulcrum than the pin to which is swivellingly attached the piston link of the upper piston, both pistons reciprocating in substantially vertical directions, and the lower piston 80 sweeping out a greater volume than the upper, the whole being mounted on suitable framing whose members are secured together and to said bed-plate, together with suitable mechanism for operating the various valves 85 and functional details substantially as represented and for the purpose set forth.
